DESIGN FOR A PICTURE CARRYING BADGE

Max Feilman, New York, N. Y.

Application January 12, 1942, Serial No. 195,122

Term of patent 7 years

To all whom it may concern:

Be it known that I, Max Fellman, a citizen of the United States and residing at New York city, in the county of the Bronx and State of New York, have invented a new, original, and ornamental Design for a Picture Carrying Badge, of which the following is a specification, reference being had to the accompanying drawing, forming part thereof.

Fig. 1 is a plan view of a picture carrying badge, showing my new design.

Fig. 2 is a side view thereof.

The characteristic features of my design reside in the portion shown in full lines.

I claim:

The ornamental design for a picture carrying badge, substantially as shown and described.

MAX FELLMAN.
